SEWING MACHINE GUARD

Matthew Murino, New York, N. Y.

Application June 1, 1940, Serial No. 338,327

2 Claims. (Cl. 112—261)

This invention relates to a sewing machine guard.

The essential object of the invention is the production of a sewing machine guard, which can be easily positioned and maintained in place on the table of the sewing machine without connecting it to said table by any means.

The second object of the invention is the production of a sewing machine guard, which will protect the operator from contacting with the flywheel and belt of the sewing machine and their appurtenances, while the machine is in operation and which will permit the inspection and adjustment of the appurtenances of the flywheel and pulley when required.

The third object of the invention is the production of a sewing machine guard which will prevent the cloth or other material that is being sewed coming in contact with the flywheel, pulley and belt of the machine while the latter is in operation.

Other objects of the invention will be apparent from the drawings, specification and claims of the application.

In the drawings Fig. 1 shows a fragmentary portion of a sewing machine and a section of the guard as on the line 1, 1 of Fig. 2; Fig. 1a is an enlarged fragmentary portion of Fig. 1; Fig. 2 represents a partial left hand side view of Fig. 1 and section of Fig. 1 on the lines 2, 2 and 2c; Fig. 2a indicates an enlarged fragmentary portion of Fig. 2; Fig. 2b indicates an enlarged fragmentary portion of a supplementary side wall of the guard and partial section of Fig. 1 on the line 2b, 2b; Fig. 3 shows a top view of Fig. 2 partly in section as on the line 3, 3 of Fig. 2. Fig. 4 represents a side view of the guard as viewed in the direction of the arrow 4 of Fig. 1 with a modification and section on the line 4a of Fig. 5 and Fig. 5 is a partial fragmentary section of Fig. 4 on the line 5, 5.

Referring to Figs. 1 to 3 a fragmentary portion of a sewing machine is shown at 20 with its driving shaft 21 and its leg 22. The latter is cut away as shown at 25 to provide a seat for the collar of locking shaft 55 to be described.

The table of the sewing machine is indicated in section at 28.

The sewing machine guard comprises a housing designated in its entirety by the numeral 30. The housing 30 comprises the main outer side wall 31, curved at its upper portion as indicated at 32, and the vertical ends 33 and 34. A clearance opening 35 is indicated in the side wall 31. A spacing strip 36 is fastened to the outer face of

the side wall 31 at its lower end. In the side wall 31 is also shown the circular clearance opening 37, with the horizontal extensions 38 and 39. To the wall 31 is fastened the spring clamp having the prongs 40 and the body portion 40a.

From the side wall 31 extends at right angles thereto the rear wall 41, with the curved upper portion 42, and the latter extends to a vertical plane extending through the axial center of the wall 31 forming the end 44.

The wall 41 has integral therewith and at right angles thereto the peripheral inner side wall 46 of the housing 30.

By means of the construction described, the 15 housing 30 is open at its front end and at its inner side. The shaft 21 extends into the housing 30 and has fastened thereto the flywheel 50 with its belt pulley 51. The pulley 51 is driven in the usual way by the belt 52.

20 A locking shaft 55 is shown with the threaded portion 56 which is in engagement with the leg 22 and is indicated with the collars 57, 58, 59 and 60.

An angle shaped supplementary side wall is 25 designated in its entirety by the numeral 65. The side wall 65 comprises the vertical member 66 with the clearance opening 66a, see Fig. 3, similar to 35, and the horizontal member 67. One end of the horizontal member 67 is indicated, see Fig. 3, at 68 and its other end is shown at 69, 70 and 71. In the vertical member 66 of the angle shaped wall 65 is indicated an opening 76, similar to 31 and has the extensions 78 and 79 respectively similar to the extensions 38 and 39.

30 35 A spring clamp with the prongs 80 and the body portion 81 has the latter fastened to the member 66.

The locking shaft 55 enables the main outer side wall 31 of the housing 30, and the member 66 of the supplemental side wall 65 to be detachably and securely locked to the leg 22 of the sewing machine.

The modified housing of the guard for the sewing machine, see Figs. 4 and 5, is indicated in its 45 entirety by the numeral 82 and comprises the main outer side wall 83, with the clearance opening 84 similar to 35, the rear wall 85 similar to 41 and the peripheral inner side wall 86 similar to 46.

The wall 83 has integral therewith and at right angles thereto the horizontal member 87.

Referring to Figs. 1 to 3 the horizontal member 67, of the side wall 65, has positioned thereon the foundation plate 90 of a bobbin winding ap-

paratus, which latter is well known, but will be described.

The plate 90 is indicated with the longitudinal edges 92, 93 and 94, and the end 95. The other end of plate 90 is similar to the ends 69 and 70 of the member 67 and the plate 90 is further shown with the curved portion 96. The plate 90 has extending therethrough the elongated openings 100, and clamping screws 105 extend through the openings 100. The screws 105 engage the horizontal member 67 of the supplementary side wall 65, to adjustably clamp the foundation plate 90 to said horizontal member 67.

Referring to Figs. 4 and 5 the foundation plate is again indicated at 90, and is fastened to the horizontal member 87 of the outer side wall 83, by the clamping screws 105a, which extend through the openings 100a of the plate 90.

In the modification shown in Figs. 4 and 5, the locking shaft 55 is omitted, and the horizontal member 87 is fastened to the table 28 by the screws 110.

The foundation plates 90, of both forms of the invention of the bobbin winding apparatus are indicated with the journal brackets 115, in which is pivoted the lower portion of the barrel 116, by means of the pivot 117. The upper end of the barrel 116 has integral therewith the crank arm 118. The barrel 116 has a spring actuated plunger 120 therein, which bears on the plate 90. In the upper end of the barrel 116, is journaled the shaft 122. One end of the shaft 122 carries a bobbin not shown and to the other end of said shaft is fastened the pulley 125. From the foundation plate 90, extends the bracket 126. A link 128 has one end pivoted to the pin 129 extending from the bracket 126. The link 128 has formed therewith the projection 130.

A link 132 with the projection 133, has one end connected to the link 128 by the pivot 135, and its other end is pivoted to the crank arm 118. A spring guide 140, is carried by the projection 133 of the link 132. Adjacent to the end 95, of the plate 90, is fastened the bracket with the horizontal member 142, and the vertical member 143, having the opening 144. A shaft 146 extends from the member 143 and has journaled thereon the pulley 148.

It will be noted that when the pulley 125 of the bobbin winding apparatus is in its operative position as shown in the drawings, that it bears against the belt 52, to be driven by the latter. The pulley 125 can be spaced from the belt 52 by collapsing the links 128 and 132 in the usual way, that is to say by lifting the link 128, by means of the projection 130.

To locate the housing 30 in place, Figs. 1 to 3, the operator positions it over the flywheel 50 and its appurtenances, with the lower edges of the walls 31, 41 and 46 bearing on the table 28. The housing 30 is then moved forwardly in the direction of the arrow A, Fig. 2 until the clearance opening 37 is axially in line with the locking shaft 55. The housing 30 is then moved to the left in the direction of the arrow B, Fig. 1 until the col-

lars 58 and 59 are positioned in line with the opposite faces of the wall 31. The housing 30 is then again moved in the direction of the arrow A, until the closed end of the extension 38 bears against the locking shaft 55, see Fig. 2. When the housing 30 is in the position just described, the spring clamp having the prongs 40, holds the outer side wall 31 in detachably locked position.

The operator next clamps the vertical member 66 of the supplementary side wall 65 in place, by locating its opening 16 axially in line with the locking shaft 55 and then moving the angle shaped supplemental side wall 65 in the direction of the arrow A, Fig. 2, until the closed end of the extension 78 bears against the locking shaft 55. In this position the prongs 80 clamp the collar 60, and the side wall 65 is detachably clamped in position.

The purpose of the extensions 39 and 79 is to permit the guard to be further moved in a direction opposite to the arrow A, Fig. 2 if desired for inspection of the appurtenances of the guard.

Various modifications may be made in the invention and the present exemplifications are to be taken as illustrative and not limitative there-

of. Having described my invention I claim:

1. In a guard for a sewing machine and the like the combination of a housing comprising a main outer side wall having a clearance opening with extensions, a rear wall extending from said main outer side wall, an inner side wall extending from said rear wall, a locking shaft extending from the sewing machine and having a pair of collars integral therewith, said locking shaft adapted to be detachably seated in one of the extensions of the openings of the said main outer side wall and said collars adapted to be located adjacent to the faces of said outer side wall to maintain the latter in operative position.

2. In a guard for a sewing machine and the like the combination of a housing comprising a main outer side wall having a clearance opening with an extension, a rear wall extending from said main outer side wall, a peripheral inner side wall extending from the rear wall, an angle shaped supplemental side wall adjacent to said main side wall, said supplemental side wall comprising a vertical member and a horizontal member, said vertical member having a clearance opening with an extension, a locking shaft extending from the sewing machine, said shaft having three collars on its outer end, a pair of said collars adapted to bear on the opposite faces of said main side wall and a pair of said collars adapted to bear on the opposite faces of the vertical member of the supplemental side wall, a spring clamp extending from the main outer side wall adapted to lock with one of the collars on the said locking shaft and a spring clamp extending from the vertical member of the supplemental side wall and adapted to lock with one of the other collars of the locking shaft.
